UNITED STATES PATENT OFFICE.

CHARLES B. JAHNKE, OF BELOIT, WISCONSIN, ASSIGNOR TO FAIRBANKS, MORSE & CO., OF CHICAGO, ILLINOIS, A CORPORATION OF ILLINOIS.

IGNITION SYSTEM.

Application filed October 9, 1924. Serial No. 742,630.

My invention relates to improvements in ignition systems, and more particularly to improvements in timers in high tension ignition systems as used on internal combustion engines.

The object of my invention relates to means of simple and inexpensive construction for operating a timer in a high tension ignition system.

10 The advantages of my method of timing are many, but the chief advantages are simplicity of construction and operation and ease of adjustment. Heretofore the timing in high tension ignition systems has been 15 secured by means of complicated devices which require skill and practice in adjustment and which are expensive to construct. In my system I make use of a cam which is preferably one of those used to operate a 20 valve, in the case illustrated the exhaust valve cam is used, and make the contact in the low tension circuit of the ignition system by means of a collar on the valve rod and a contact insulated from the rod. Timing 25 is secured by simply adjusting the valve cam so that the recess in the cam operates the contact at the desired time.

Although my invention consists largely in the construction and arrangement of parts 30 hereinafter described and particularly pointed out in the claims, yet I do not limit my invention to the precise form, construction or arrangement of parts shown or the several parts thereof, inasmuch as various alterations 35 may be made without changing the scope of my invention.

My improvements consist in the construction, arrangement and combination of parts 40 as hereinafter fully, clearly and concisely described and illustrated by the accompanying drawings (2 sheets), in which Fig. 1 is a partially cut-away elevational view of an internal combustion engine employing my invention, illustrating the method used of 45 operating the valve rod and showing clearly the cam used. Fig. 2 is a partially sectional plan view of the same engine illustrated in Fig. 1 showing my timing arrangement in 50 sectional view. Fig. 3 is an enlarged sectional view of my timing arrangement as illustrated in Fig. 2 but showing it more clearly.

55 Referring by numerals to the drawings, the cam 5 is driven by the half-speed cam gear 6, attached to shaft 7. Gear 6 is pref-

erably operated by the crank shaft 8 through gear 9. Cam 5 preferably engages roller 10, carried by rocker 11, this rocker being pivoted on pin 12. The movement of rocker 11 operates the exhaust rod 13, the point of contact between the rocker and the rod being indicated at 14. Exhaust rod 13 operates exhaust valve 15, located in the cylinder head 16 of the engine by means of the rocker 17, pivoted at 18. The cylinder head end 19 of the exhaust rod is supported in a socket 20 of rocker 17 and an adjustment for the length of this rod is provided at 21. The exhaust valve spring 22 serves to close the exhaust valve and also to return the exhaust rod and rockers to their position of rest after being lifted by the cam 5. Sufficient clearance is given, however, so that the exhaust valve will be free to seat.

The high tension ignition system is controlled by a timer, and in my invention I have mounted the operating element of this timer on a valve rod, in this case the exhaust valve rod. This consists in a collar 23 which is carried by the exhaust rod 13 but which is preferably held away from contact with insulated contact plate 24 at all times during the revolution of the engine excepting the short period when it is desired to secure ignition in the cylinder. Collar 23 which communicates with a ground through the exhaust rod 13 and the body of the engine, is brought in contact with the insulated contact plate 24 when roller 10 on the exhaust rod connection drops into the recess 25 in cam 5. Since contact plate 24 is connected to the other or non-grounded side of the low tension circuit of the ignition system, this contact establishes electrical connection in that circuit and completes the circuit, thereby supplying current to the primary of the spark coil, which gives rise to the high tension current in the secondary of the coil causing ignition to occur in the cylinder by means of a suitable spark plug. It is evident that while I show a cam having a recess therein any suitable shape of cam may be employed.

It is evident from the foregoing description that the time of the spark, also its duration, is controlled by the position and size of recess 25 in cam 5. 26 is the insulating material separating the metal contact plate 24 which is attached to timer cover 27 from the grounded detent bracket 28. Wire 29 is 110

attached to the metal timer cover 27 and is the connection from the non-grounded side of the low tension circuit. Torsional spring 30 encircling the rocker fulcrum 18 acts independently of the exhaust valve spring 22 to hold the roller 10 against the low part of cam 5 and to force it into recess 25, thereby grounding the circuit.

A governor mechanism may be employed such as described in my application filed October 9, 1924, Serial Number 742,631, driven from gear 6 by means of a pinion 31. This pinion rotates suitable governor weights (not shown) which apply an axial movement to spindle 32, this spindle preferably contacts with one end of a pivoted member 33, and when the speed becomes excessive, rotates this member about its pivot until the end 34 engages with shoulder 35 of valve rod 13, thereby preventing the valve from closing and also preventing any electrical contact between collar 23 and contact plate 24.

I claim:

1. In an ignition system, a valve-operating device having a rod, electrical contacts about said rod, one of said contacts being carried by a bearing element for said rod and adapted to serve as a motion-limiting means therefor, and means operated by said valve-operating device for periodically making electrical connection between said contacts.

2. In an ignition system, in combination with a valve-operating rod, an annular contact member on said rod for periodically closing the low tension circuit of said ignition system, said member being operated by said valve-operating rod, and constituted by an enlarged annular portion thereof.

3. In an ignition system, in combination with a valve rod, a bearing element therefor, an electrical contact member around said rod, a contact member carried by said bearing element and not in electrical connection with said rod, and means for making a periodical electrical connection between said contact members.

4. In an ignition system, in combination with a valve rod and a stationary supporting member therefor, an annular electrical contact member connected to said rod, an electrical contact member on said stationary supporting member, insulated therefrom, and adapted as an abutment for said annular member, and means for making a periodical electrical connection between said contact members.

5. In an ignition system, in combination with a valve rod, a bearing member there-

for, an annular contact member carried by said rod, a contact member carried by said bearing, a cover for said members, a cam operating said rod, and a spring-pressed member acting on said rod whereby a periodical electrical connection is made between said contact members.

6. In an ignition system, a timer comprising in combination with a spring-pressed valve rod and a cam adapted to operate said rod, an annular stationary contact plate insulated from said rod, and adapted as a motion-limiting means therefor, and a contact collar connected to said rod and adapted to move therewith to make periodical electrical connection with said stationary contact plate.

7. In an ignition system, in combination with a spring-pressed valve rod and a recessed cam adapted to operate said rod, an annular stationary contact plate insulated from said rod, and a contact collar connected to said rod and adapted to move therewith to make periodical electrical connection with said stationary contact.

8. In an internal combustion engine, a timer comprising in combination, a valve rod, an annular electrical contacting member thereon, a rod bearing, a stationary contacting member mounted on said bearing and serving as an insulated abutment for said annular contact member and means for making periodical electrical contact between said members.

9. In an internal combustion engine, a timer comprising in combination, a valve rod, an electrical contacting collar thereon, a stationary contacting plate, a bearing for said rod, said plate and bearing constituting an insulated abutment for said collar, means for making periodical electrical contact between said collar and said plate, and a cover for said contact elements.

10. In an ignition system for an internal combustion engine, a cam, a valve rod actuated thereby, an annular contact element concentrically surrounding said rod, comprising a timer bracket, a contact collar, insulating material therebetween, a cover for said contact collar, a terminal carried by said cover; an additional annular contact element surrounding said rod comprising an annular contact member, one of said contact elements being stationary, the other adapted to be carried by said rod, whereby the movement of said rod effects a periodical electrical connection between said contact elements.

CHARLES B. JAHNKE.
